UNITED STATES PATENT OFFICE.

BELTON L. LUTZ, OF READING, PENNSYLVANIA, ASSIGNOR TO INTERNATIONAL MONEY MACHINE COMPANY, OF READING, PENNSYLVANIA, A CORPORATION.

TYPE-CARRIER.

1,396,938.

Specification of Letters Patent. Patented Nov. 15, 1921.

Application filed September 23, 1920. Serial No. 412,205.

To all whom it may concern:

Be it known that I, BELTON L. LUTZ, citizen of the United States, residing at Reading, in the county of Berks and State of Pennsylvania, have invented certain new and useful Improvements in Type-Carriers, of which the following is a specification.

The present invention relates to improvements in type carriers of that character which are embodied in the printing mechanisms of calculating or adding and listing machines, such as that disclosed by Patent No. 1,192,721, which was granted on July 25, 1916 to Nelson White.

One of these type carriers is ordinarily provided for each denomination or bank of keys and the type carriers are associated with the numeral wheels of the accumulator so that they will be automatically moved to bring the proper type member into printing position. The previous practice has been to provide each type member with an individual spring for normally holding it in a retracted position, and since there are ten type members upon each carrier and a separate carrier for each denomination, it will be understood that this requires a large number of small springs. Not only does the use of such a large number of small springs increase the cost of manufacture and assembling, but the springs are liable to get out of order and close attention is required to keep the mechanism in operative condition.

One of the objects of the present invention has been to overcome this difficulty by the provision of novel type retracting means in which a single spring member serves to hold all of the type members upon one of the type carriers yieldably in a retracted position, thereby reducing the cost of production and providing a construction which is more dependable and less likely to get out of repair.

Further objects of the invention are to provide a device of this character which is comparatively simple and inexpensive in its construction, which can be easily assembled and taken apart, which is dependable in its operation, and which is not liable to get out of repair.

With these and other objects in view the invention consists in certain combinations, arrangements and associations of the parts, as will more fully appear as the description proceeds, the novel features thereof being pointed out in the appended claims.

For a full understanding of the invention reference is to be had to the following description and accompanying drawings, in which:

Figure 1 is a side elevation of a type carrier constructed in accordance with the invention, portions being broken away and shown in section to illustrate more clearly the details of construction.

Fig. 2 is a perspective view of one end of the type carrier, the retaining cap plate for the type members being partially removed.

Fig. 3 is an enlarged transverse sectional view on the line 3-3 of Fig. 1, looking in the direction of the arrows.

Fig. 4 is an enlarged detail sectional view on the line 4-4 of Fig. 1, looking in the direction of the arrows.

Figs. 5 and 6 are detail views of one of the levers which carry the type retracting bar.

Fig. 7 is a detail view of a fragmentary portion of the type retracting bar showing one of the sockets which is utilized for obtaining a loose connection with the levers.

Fig. 8 is a detail view of one of the type members.

Fig. 9 is a side elevation of a complete type carrier, the platen and hammer of the printing mechanism being illustrated diagrammatically in operative relation thereto.

Corresponding and like parts are referred to in the following description and indicated in all of the views of the drawing by like reference characters.

Specifically describing the present embodiment of the invention, the numeral 1 designates the stock or body of the type carrier, said body having an elongated formation, and being ordinarily mounted in a vertical position, as indicated by Fig. 9, so that it can be moved up and down the necessary amount to bring the proper type mem-

ber 2 into position for printing upon a strip of paper rolled upon the platen P. The type carrier body which has been illustrated is similar in its general configuration to that used in the adding and listing machine disclosed by Patent No. 1,192,721, which was granted to Nelson White on July 25, 1916. Longitudinal slots 3 are provided in the type carrier body and these slots are intended to engage fixed guide members so that the type carrier is properly directed in its up and down reciprocating movements. The type members 2 are provided with printing faces 2^a comprising the various numerals from "0" to "9," inclusive, and all of the type members are normally held yieldably in a retracted position under normal conditions. As the type carrier is moved up and down by the mechanism of the calculating machine the printing faces of the various type members 2 are brought into operative position for printing against the platen. In the printing operation of the machine the type member 2 which is in operative position is struck by the hammer H and forcibly moved toward the platen so as to make an impression upon the paper which is wound upon the platen. This operation is well known in the art and is illustrated diagrammatically by Fig. 9. After striking the type member the hammer is swung back into inoperative position and the type member again retracted into its original position.

The upper end or head of the type carrier body is provided with side flanges 4 which are correspondingly notched at 5 to receive the type members 2. A retaining cap plate 6 fits over the type members so that the latter are confined between the retaining plate and the type carrier body and held slidably in position within the notches 5. The retaining plate 6 may have longitudinal ribs 6^a pressed outwardly therefrom in such a manner as to stiffen the plate and reduce the frictional engagement between the plate and the type members. The extremities of the retaining plate 6 are provided with end flanges 7 which are suitably notched at 8 to interlock with tongues 9 projecting longitudinally from the side flanges 4 of the type carrier body. Provision is thus made for securing the retaining plate in position by a simple interlocking connection and without the necessity of using any separate fastening members such as rivets or screws.

The type members 2 have the sides thereof which face toward the body 1 notched or cut away at 10 to provide a clearance space for the retracting bar 11, said bar extending longitudinally of the type carrier body 1 and engaging shoulders provided by the notches 10 of the type members to hold all of the type members 2 in a retracted position under normal conditions. The retracting bar 11 is provided at points toward opposite

ends thereof with laterally opening sockets 12 which loosely receive rounded heads 13 at the swinging ends of parallel levers 14. The two levers or arms 14 are similar and interchangeable and have the opposite ends thereof pivotally connected at 15 to the type carrier body. The type retracting bar 11 is thus mounted in such a manner that it is free to move laterally into a position parallel to itself, and the swinging arms 14 are arranged at a sharp angle to the retracting bar so that this lateral movement of the retracting bar will be accompanied by a minimum longitudinal movement thereof, thereby reducing the frictional engagement between the retracting bar and the shoulders of the type members.

One end of the type retracting bar 11 is provided with an eye 11^a which is connected by a tension spring 16 to an arm 17 projecting from the type carrier body 1, said arm and eye being bent or twisted so that the spring will be properly positioned to act freely without having a binding engagement with any part of the machine. This one tension spring 16 pulls longitudinally upon the type retracting bar 11 and operates to swing the same toward the rear edge of the type carrier body 1 so that the type members 2 are all held in a retracted position. However, when any selected one of the type members is struck by the hammer H of the printing mechanism the particular type member is forced into a printing position, as indicated by Fig. 9. The type retracting bar 11 will, of course, be moved with the type member, but the mounting thereof is such that it moves into a position parallel to itself and is always held at substantially right angles to the type members. Those of the type members 2 which are not struck by the hammer will remain in a retracted position owing to their inertia and frictional engagement with the parts of the type carrier, although should any of these type members be shifted out of position no harm will be done, since as soon as the hammer H is moved back into inoperative position the type retracting bar 11 will be swung back to its original position by the spring 16, and all of the type members will then be held yieldably in retracted position.

The parallel levers or arms 14 which carry the type retracting bar 11 are shown as provided at the swinging ends thereof with stop arms 18 which are arranged to engage one of the side flanges 4 of the type carrier body and thereby limit the lateral movement of the type retracting bar 11 and the throw of the type members when struck by the hammer H. This mechanism eliminates the necessity of providing an individual spring for retracting each of the type members, and not only is the cost of manufacturing the device greatly reduced, but there is less

liability of the construction getting out of order.

While one particular embodiment of the invention has been shown and described for the purpose of illustrating the idea of the invention, it will be understood that numerous modifications and changes can be made in the details of construction without departing in any manner from the spirit of the invention.

Having thus described the invention, what I claim as new and desire to secure by Letters Patent is:—

1. The combination with a type carrier body and a series of movably mounted type members carried thereby, of means including a single spring element for normally holding the type members yieldably in inoperative position, said type members being adapted to be brought individually into position to print.

2. The combination with a type carrier body and a series of movably mounted type members carried thereby, of a single retracting member engaging all of the type members to hold them yieldably in a retracted position, said type members being adapted to be brought individually into position to print.

3. The combination with a type carrier body and a series of movably mounted type members thereon, said type members being provided with shoulders, of a yieldably mounted retracting bar engaging the shoulders of the several type members to hold them normally in inoperative position, said type members being adapted to be brought individually into position to print.

4. The combination with a type carrier body and a series of movably mounted type members thereon, each of the type members being provided with a shoulder, of a yieldably mounted retracting bar engaging the shoulders of the several type members to hold them normally in inoperative position, and means for mounting the retracting bar so that it always moves in a position parallel to itself.

5. The combination with a type carrier body and a series of movably mounted type members thereon, each of the type members being provided with a shoulder, of a retracting bar extending transversely of the type members and engaging the shoulders, substantially parallel levers carrying the retracting bar and causing it to move in a position parallel to itself, and yielding means normally holding the retracting bar in operative position.

6. The combination with a type carrier body and a series of movably mounted type members thereon, of a retracting bar extending transversely of the type members and engaging the same, means for causing

the retracting bar to move in a position parallel to itself, stop means for limiting the movement of the retracting bar, and yielding means normally holding the retracting bar in operative position.

7. The combination with a type carrier body and a series of movably mounted type members thereon, of a retracting bar extending transversely of the type members and engaging the same, substantially parallel levers mounted upon the type carrier body and engaging the retracting bar to cause it to move in a position parallel to itself, a yielding member connected to the retracting bar for normally holding it in operative position, and stop arms upon the levers for limiting the movements thereof.

8. The combination with a type carrier body and a series of movably mounted type members thereon, of a retracting bar extending transversely of the type members and engaging the same, said retracting bar being provided at spaced points with laterally opening sockets, substantially parallel levers pivotally mounted upon the type carrier body and provided at their swinging ends with rounded heads which engage the sockets whereby the retracting bar is caused to move in a position parallel to itself, and yielding means for normally holding the retracting bar in operative position.

9. The combination with a type carrier body and a series of movably mounted type members thereon, of a retracting bar extending transversely of the type members and engaging the same, said retracting bar being provided at spaced points with sockets, parallel levers pivotally mounted upon the type carrier body and provided at their swinging ends with rounded heads which are received within the sockets of the retracting bar whereby the latter is caused to move in a direction parallel to itself, stop arms projecting from the levers for engagement with the type carrier body to limit the movement of the retracting bar, and yielding means engaging the retracting bar to normally hold it in operative position.

10. The combination with a type carrier body and a series of movably mounted type members thereon, of a retaining plate fitted over the type members to hold them in position, and cooperating interlocking tongues and cut away portions at each end of the retaining plate and adjacent portions of the type carrier for detachably holding the retaining plate in position upon the type carrier body.

11. The combination with a type carrier body formed of sheet material and having notched side flanges, type members slidably mounted within the notches of the side flanges, and a retaining plate formed of sheet material and fitting over the type

members, said retaining plate being formed with end flanges and the flanges of the two members being formed with interlocking tongues and notches which detachably hold the retaining plate in position.

12. The combination with a type carrier body and a series of movably mounted type members which are adapted to be brought

individually into printing position, of a single spring member, and means associated with the said spring member and type members for normally holding all of the type members yieldably in inoperative position.

In testimony whereof I affix my signature.

BELTON L. LUTZ.
